UNITED STATES PATENT OFFICE.

JAMES HENRY SHELDON, OF WARREN, MINNESOTA.

BAND-CUTTER AND FEEDER.

SPECIFICATION forming part of Letters Patent No. 339,815, dated April 13, 1886.

Application filed August 10, 1885. Serial No. 174,025. (No model.)

To all whom it may concern:

Be it known that I, JAMES HENRY SHELDON, of Warren, in the county of Marshall and State of Minnesota, have invented certain new and useful Improvements in Band-Cutters and Feeders, of which the following is a full, clear, and exact description.

Reference is to be had to the accompanying drawings, forming part of this specification, in which similar letters of reference indicate corresponding parts in all the figures.

Figure 1 is a plan view of my improved feeding and band-cutting attachment, showing in dotted lines the position of the thrashing-cylinder. Fig. 2 is a side elevation of the same, part being broken away. Fig. 3 is a transverse vertical section of the same, taken through the line *xx*, Fig. 2. Fig. 4 is a longitudinal vertical section of the same, taken through the line *yy*, Fig. 1. Fig. 5 is a transverse vertical section of the same, taken through the line *zz*, Fig. 4.

The object of this invention is to provide band-cutting and feeding attachments for thrashing-machines, constructed to carry the bundles forward, cut the bands, spread the grain, and feed it evenly to the thrashing-machines.

The invention consists in the construction and combination of the various parts of the feeding and band-cutting attachments, as will be hereinafter fully described and claimed.

A represents part of the frame of a thrashing-machine, to the upper forward corners of which are rigidly attached the ends of two horizontal bars, *B*.

To the outer ends of the bars *B* are rigidly attached the lower ends of two uprights, *C*.

From the upper ends of the uprights *C* are hung, by means of a rod, *D*, the upper ends of two hangers, *E*, which are made shorter than the uprights *C*, as shown in Fig. 5. The uprights *C* and the hangers *E*, at their upper ends, are kept in proper relative positions by nuts *D'*, screwed upon the supporting and hinging rod *D*, upon the outer and inner sides of the said ends. The outer ends of the bars *B* and the lower ends of the uprights *C* are kept in proper relative positions by a rod, *x*, and nuts *y*, screwed upon the said rod at the opposite sides of the said ends.

To the lower parts of the hangers *E* are rigidly attached the inner ends of the side

bars, *F*, to the lower edges of which are attached three (more or less) cross-bars, *G*.

55

To the upper edges of the cross-bars *G* is attached the close bottom *H* of the carrier.

To the outer part of the side-bars or the bottom of the carrier are hinged the upper ends of legs *w*, to support the said outer part 60 when in a working position. With this construction, when the machine is not in use and when passing from place to place, the carrier can be swung over the chute, hereinafter described, into the position indicated by dotted 65 lines in Fig. 2, the legs *w* folding down upon the said carrier, as shown. The legs *w* serve as handles in adjusting the carrier.

To the inner and outer ends of the lower edges of the side bars, *F*, are attached bearings for the shafts *I*, to which, at the inner sides of the said side bars, are attached pulleys or rollers *J*, around which pass endless 70 belts *K*.

To the endless belts *K* is attached an endless 75 apron, *L*, of canvas or other suitable material, to receive the grain-bundles and carry them inward toward the thrashing-machine.

To the endless apron *L* and the belts *K* are attached cross-bars *M*, placed at suitable distances apart, and provided with teeth *N*, to engage with the bundles of grain and carry them 80 forward with certainty.

To one end of the inner shaft, *I*, is attached a large gear-wheel, *O*, the teeth of which mesh 85 into the teeth of the smaller gear-wheel, *P*, attached to the end of the shaft *Q*. The shaft *Q* revolves in bearings attached to the side bars, *F*, and upon it is placed a number of circular cutters, *R*, which are kept at the 90 proper distance apart by hubs *S*, attached to them, or by sleeves interposed between them and which are secured to the said shaft by set-screws *T*, passing through the said hubs and resting against the said shafts *Q*, or by 95 other suitable means. The hubs *S* are countersunk to receive the heads of the set-screws *T*, so that the straw will not be liable to be caught by the said screw-heads and wound around the shaft. With this construction, as 100 the bundles of grain are being carried inward by the carrier, their bands will be cut and the said bundles will be cut longitudinally into sections or slices.

To the upper sides of the inner parts of the 105 side bars, *F*, are attached side boards, *U*, to pre-

vent the grain from falling off at the sides of the carrier. The grain passes from the inner end of the carrier to the inclined chute interposed between the said carrier and the thrashing-machine, and which is formed of a bottom, 5 V, and side boards, W.

To the upper and lower parts of the lower side of the bottom V are attached cross-bars X, having at their ends projecting rods Y, 10 which slide in bearings Z. The upper bearings Z are attached to the upper side of the outer parts of the bars B, and the lower bearings Z are attached to the thrasher-frame A a little below the said bars B. The rods Y of 15 the lower cross-bars, X, are detachable, and are secured in place in the ends of the said cross-bar by set-screws a, so that the said rods can be readily detached to allow the inner end of the chute to be swung down to give access to 20 the cylinder and concave of the thrasher, the said chute hanging in a vertical position at the inner end of the carrier.

To the upper side of the chute-bottom V is attached a number of parallel longitudinal 25 ribs, b, having the upper sides of their upper ends beveled. The ribs b are designed to cause the grain-stalks to pass down the chute endwise and to assist in spreading the stalks. To bearings c, attached to the side 30 bars, B, is journaled a shaft, d. To the shaft d are attached hubs e, having radial lugs or arms, to which are bolted wings, blades, or fans f, to come in contact with the loose grain as it passes down the chute and spread it 35 over the chute-bottom. One journal of the beater-shaft d projects, and to it is attached a pulley, g, which is driven by the contact of a belt, h, with its upper and lower sides. The belt h passes around and receives motion from 40 a pulley, i, attached to a journal of the thrasher-cylinder. The belt h also passes around and gives motion to a pulley, j, attached to the projecting journal of the cutter-shaft Q, so that the cutters will be driven 45 from the thrasher-cylinder.

To the horizontal bar B is pivoted a lever, k, to the forward end of which is pivoted a pulley, l, the face of which rests against the lower strand of the belt h, so that the tension 50 of the said belt can be regulated by operating the said lever. The tension-pulley l is secured in any position into which it may be adjusted by a pin, m, which passes through a hole in the outer arm of the lever k and enters one of a number of holes in the side bar, B.

To the middle part of the lower side of the chute-bottom V are attached supports n, to which is pivoted the inner end of a pitman, o. The outer end of the pitman o is pivoted to 60 the crank-pin p, attached to a wheel, q, secured to the lower end of the inclined shaft r. The crank-wheel q is designed to be made so heavy as to serve as a balance-wheel to give steadiness of motion to the chute V W. The 65 shaft r revolves in bearings attached to the horizontal bar B and to the upright bar C.

To the upper end of the shaft r is attached a bevel gear-wheel, s, the teeth of which mesh into the teeth of the bevel gear-wheel t, attached to the inner carrier-shaft, I, so that the chute V W will be vibrated from the said carrier-shaft. With this construction the vibration of the chute V W, in connection with the chute-ribs b and the beater d e f, will spread the loose grain evenly over the chute-bottom and cause it to pass to the thrasher in a sheet of uniform thickness. The upper side of the lower edge of the chute-bottom V is rabbeted to receive the guard-plate u, the lower edge of which projects beyond the lower edge 80 of the said chute-bottom, so as to overlap the upper edge of the concave v of the thrasher, and thus prevent any of the grain from falling to the ground between the lower edge of said chute-bottom and the upper edge of the 85 said concave. The guard-plate u is hinged at its upper edge to the chute-bottom V, so that it can be readily turned up upon the said bottom to be out of the way when it is desired to allow the lower end of the chute to swing 90 downward.

Having thus fully described my invention, I claim as new and desire to secure by Letters Patent—

1. In a band-cutter and feeder, the combination, with frame A and bars B, of the transversely-reciprocating chute V W, longitudinal ribs b, the projecting rods Y on the under side of the chute, bearings therefor on the frame and bars, the shaft r, a wheel, q, secured thereto and provided with a crank-pin, p, the pitman o, connecting the crank-pin and the chute, and gearing for driving the shaft r, substantially as set forth. 95

2. The combination, in a band-cutter and feeder, with the transversely-reciprocating chute having longitudinal ribs on its bottom and means for operating the said chute, of a rotary beater journaled over the chute, substantially as set forth. 105

3. In a band-cutter and feeder, the combination, with the thrasher-frame A, the horizontal bars B, and the upright bars C, and the bearings x, of the chute V W, the cross-bars X, projecting fixed and detachable rods Y, the 115 ribs b, attached to the chute-bottom, and the rotary beater d e f, substantially as herein shown and described. 110

4. The combination, with the thrashing-cylinder and concave, the frame A, and bars B, of the downward-swinging chute having a hinged connection at its upper end with the bars B, and removably connected at its lower end to the frame adjacent to the concave, of the guard u, overlapping the adjacent edges 125 of the chute and concave, and constructed to fold upward, substantially as set forth. 120

JAMES HENRY SHELDON.
